DESIGN FOR A VELOCIPED

Bert J. Anderson, Hammond, Ind.

Application August 12, 1935, Serial No. 58,088

Term of patent 14 years

To all whom it may concern:

Be it known that I, Bert J. Anderson, a citizen of the United States, residing at Hammond, in the county of Lake and State of Indiana, have invented a new, original, and ornamental Design for a Velocipede, of which the following is a specification, reference being had to the accompanying drawing, forming part thereof.

Fig. 1 is a side elevational view of a velocipede, showing my new design;

Fig. 2 is a front elevational view thereof with the wheels removed;

Fig. 3 is a rear elevational view of the velocipede frame; and

Fig. 4 is a top plan view of the velocipede frame, a portion being broken away.

The dominant features of the invention reside in the streamlined and symmetrical frame and front fender shown in solid lines.

I claim:

The ornamental design for a velocipede as shown and described.

BERT J. ANDERSON.
